UNITED STATES PATENT OFFICE.

ERIC JOHNSON, OF SEATTLE, WASHINGTON.

PORTABLE ELEVATOR.

Application filed November 2, 1925. Serial No. 66,246.

This invention relates to a portable elevator which is adapted more particularly, but not exclusively, for use as a lumber stacker, and is in the nature of improvements to the 5 elevator illustrated and described in U. S. Patent No. 1,053,391, issued February 18, 1913, to H. C. Hilke.

The object of my improvements is the provision in an elevator having vertically movable chain conveyors, of devices for automatically controlling the delivery of material from the conveyor flights at various heights at either side of the elevator selectively.

15 The invention consists in the novel construction, arrangement and combination of parts hereinafter described and claimed.

In the accompanying drawings.—

Figure 1 is a front elevation; and Fig. 2 20 is a side elevation of an elevator embodying my improved devices. Fig. 3 is a view partly in front elevation and partly in vertical section of parts shown in Figs. 1 and 2, to an enlarged scale. Fig. 4 is a horizontal 25 sectional view taken on line 4—4 of Fig. 3 and illustrating in plan the carrier in the position in which it is represented by dotted lines in Fig. 3. Fig. 5 is a vertical section taken substantially on line 5—5 of Fig. 3. 30 Fig. 6 is a detail sectional view on line 6—6 of Fig. 3.

In the drawings, the reference numeral 5 represents, generally, the elevator frame which is supported by a wheeled car 6.

35 The frame 5 is formed of two substantially A-shaped members, one at each end of the car, composed of posts 7 and 8 which are inclined toward each other as shown in Fig. 1. The lower ends of said posts are 40 rigidly secured to the car 6, the upper ends of the posts of each frame member are rigidly connected together by means of couplings 9.

The frame 5 also includes suitable braces, 45 such as 10 Fig. 2, for rigidly connecting the side members in parallel relation with each other.

The posts 7 and 8 of the frame are formed, 50 desirably, of channel bars to afford ways, such as 11 in Fig. 2, in which operate endless conveyor chains 12, one for each of the frame members. At the top of the frame, 55 said chains pass over sprocket wheels 13 which are mounted upon a transverse shaft 14 which is journaled in bearings provided in the respective frame couplings 9. The

lower portions of said chains pass about guide pulleys 15.

For driving the conveyor chains, the shaft 14 is driven as by means of an endless chain 60 16 passing about a sprocket wheel 17 on said shaft and about a sprocket wheel 18 provided on a second shaft 19 which latter is driven through the medium of a train of gears 20 from a motor 21 provided on the 65 car. Attached to the respective conveyor chains 12 in spaced apart relation are pluralities of flights 22, each such flight being formed with companion arms 23 and 24 converging toward their outer ends to furnish 70 a dove-tail cavity 25 therebetween.

The operation of the elevator for elevating, by means of the conveyor chains, lumber to be piled upon the stack S Fig. 1 is as follows: Pieces of lumber, as L for example, 75 are placed upon the arms 23 in the cavities of the respective flights 22 as the latter ascend at one side of the frame in the direction denoted by the arrow in Fig. 1. When the flights pass, as at 22¹, successively over the 80 top of the frame, the lumber as indicated by L¹, is transferred from the respective arms 23 to the arms 24 and is thereby supported as the flights descend at the other side of the frame. According to the present invention 85 I provide devices for automatically delivering the lumber from the flights upon bracket arms located within convenient reach of men standing upon a stack of lumber as represented, for example, by dotted lines S in 90 Fig. 1.

For which purpose I provide at each end of the elevator a hanger 26 which is provided near its upper and lower ends, respectively, with recesses such as 27 (Figs. 4 and 6) to receive a vertically disposed track rail 28 which is rigid with the elevator frame.

The upper end of each hanger 26 is connected as by means of an eye-bolt 29 to an end 30 of a hoisting cable 31 which passes over a pulley 32 provided at the top of the frame, thence the cable extends downwardly and is coiled about a winding drum 33, one for each cable, provided upon the car 6. The drums 33 are rotatable in unison by 100 suitable means, as shown there is employed a manually operated crank shaft 34 carrying worms 35 which take with worm wheels 36 provided on the arbors of the respective drums.

In proximity of its upper end, each of 105 said hangers is formed or provided with

spaced apart bearings 37 (Fig. 5) for a bolt or pin 38 which extends through aligned apertures in adjacent ends of associated bar elements 39 of a carrier 40.

5 As illustrated, the bar elements of a carrier are disposed in parallel relation with each other and in which are journaled the axles 41 of a series of anti-friction rollers 42 of greater diameters than the widths of 10 the bar elements 39.

In proximity of its lower end each of said 15 hangers is provided with a relatively wide portion 43 from which protrude a plurality of headed studs 44, 44¹ and 44² arranged substantially as represented in Fig. 3,—that is to say, with the stud 44 located at or about

the midwidth of the respective hanger part 43 and the other studs, 44¹ and 44², located at opposite sides thereof at two elevations.

20 Said studs are selectively engageable in either of a pair of keyhole-shaped apertures 45, 45¹ provided in spaced apart relations in the ends of a bracket bar 46. Such keyhole apertures being each in the nature of a slot disposed longitudinally of the bar 46, one 25 end of each aperture being enlarged to receive the head of a selected one of said studs, the other end of the aperture being of a width to afford a sliding fit with the shank 30 of the respective stud.

A bracket bar 46 is also provided at about its midlength with a hole to receive a bolt 47 whereby the carrier 40 is connected therewith when it is desired to support the bracket bar in substantially the horizontal position in which it is represented by full lines in Figs. 1 and 3.

40 For unloading the flights to supply lumber to the stack S, the carriers 40 and bracket bars 46 at both ends of the elevator frame are arranged to occupy the relative positions in which they are represented by full lines in Figs. 1 and 3; and the conveyor chains are driven in the direction indicated by the arrow in Fig. 1. The lumber loaded into the respective flights, as hereinbefore described, is carried over the top of the frame descending at that side of the latter next to the stack S.

45 50 A board thus descending when it encounters the inclined carriers 40 has imparted thereto a horizontal movement to eject the board from the cavities of the associated flights. A board thus ejected by the carriers 55 is delivered upon the carrier rollers 42 and thence by gravitation onto the associated bars 46, from which the successively deposited boards are removed by workmen for building up the stack.

60 65 When the stack as S¹ (Fig. 1) at the opposite side of the elevator is to be supplied with lumber, said carriers and brackets are disposed at suitable heights in the relative positions in which they are represented by dotted lines 40² and 46² in Fig. 1; and the

conveyor chains are driven in the direction opposite that indicated by the arrow in the view.

For removing lumber from a stack, the carriers are disposed horizontally as denoted by dotted lines 40³ in Fig. 1 and 40⁴ in Fig. 3, in which arrangement the bracket bars are employed in the relative positions wherein they are indicated by dotted lines 46³ and 46⁴, respectively, to serve as bracket supports. When thus arranged the workmen first place the lumber upon the carriers and, while pairs of ascending flights are passing the plane of the carriers, the boards are shoved manually into the respective flight- 80 cavities 25.

In taking down lumber from the top of a stack it is to be noted that the lumber is loaded into ascending flights at the elevator's side next to the stack and lowered with the 85 descending flights at the opposite side of the elevator.

The carriers 40 and bracket bars 46 are raised or lowered into and from suitable heights by means of the hoisting cables 31, 90 one near each end of the frame, which cables are actuated in unison by operating the drums 33 through the instrumentality of shaft 34 and worm gearing 35—36. The worm gearing in the drum-operating mechanism serving to lock the drums against accidental rotation.

A hanger, carrier and bar assembly is adapted and arranged to be regulated to use for loading and unloading at different 100 sides of the elevator selectively; and, furthermore, is adapted to have the carrier and bar members disposed in positions whereat they protrude from neither side of the frame.

105 The provision of means for effecting the changes above referred to in the relative positions of the members of the referred to assembly constitute an important part of the present invention, enabling the elevator to be moved bodily in a narrow passageway between two stacks as S and S¹ in Fig. 1 for example, and permitting the handling of lumber to and from stacks at both sides of the passageway.

110 115 The manner of regulating the carrier and bar members will be understood by reference to Fig. 3: Assuming a carrier 40 is attached to the associated bar 46 at its midlength by means of the bolt 47, said bar 46 is swingable with the carrier about the pivot connection 38, from the full line positions of the respective parts in Figs. 1 and 3 into their dotted line positions 46² and 40² in Fig. 1—that is to say, from one side to the other side of the frame. The carrier and bracket bar members of each assembly thereof are secured in selected relative positions by having the proper one of the studs 44¹ or 44² engaged in one of the slots 45 120 125 130

or 45¹ at the end of the bar next to the elevator frame 5. To use the carrier horizontally as represented in dotted lines 40¹ and 40³ in Figs. 3 and 1, respectively, the 5 bolts 47 is utilized as at 47¹, Fig. 3 to connect the outer end of the carrier with the bar by means of the outermost slot 45 of the bar and have one of the studs, as 44 for example, engage in a slot at the opposite end of the bar. From the foregoing 10 it is apparent that the bar and carrier are adapted to be swung from one side to the other of the frame and to be secured in pre-arranged relations with each other as above 15 explained.

When it is desired to have the carrier and the bar disposed in inoperative positions as indicated in Fig. 1 by dotted lines 40⁴ and 46⁴, respectively, all that is necessary to do is to disengage the bar from the hanger permitting the same to depend from the carrier which latter is supported by the bolt 38.

While I have illustrated and described the 25 now preferable embodiment of the invention I do not wish to be understood as confining myself specifically thereto except as limited by the scope of the appended claims.

What I claim, is,—

30 1. The combination with an elevator frame, a conveyor chain operating vertically in said frame, and load carrying flights attached to said chain, of a hanger connected for vertical movement on the elevator frame, 35 means to regulate the height of said hanger, a carrier pivotally connected at one of its ends to said hanger, and a bracket bar pivotally connected to the hanger and to the carrier said bar being adapted to be arranged for supporting the latter interchangeably in a load holding position and in position to eject loads from the conveyor flights when the latter are in motion.

2. The combination with an elevator 45 frame, a conveyor chain operating vertically in said frame, and load carrying flights attached to said chain, of a hanger connected for vertical movement to the elevator frame, means to regulate the height of said hanger, 50 a carrier pivotally connected at one of its ends to said hanger, a bracket bar connected by either of its ends selectively to said hanger,

and means for regulating the connection of the bracket bar to the carrier for supporting at every elevation of the hanger the latter 55 interchangeably in a load holding position and in position to eject loads from the conveyor flights when the latter are in motion.

3. In an elevator, the combination with a frame, and conveyor chains provided with load carrying flights operating vertically at each end of the frame, of a hanger guided for vertical movement at each end of the frame, means to secure said hangers at selected heights, a carrier pivotally connected from one of its ends to each of the hangers for movement from one side to the other of the frame in a substantially vertical plane, and means for supporting the carriers in horizontal and inclined positions selectively 70 at either side of the frame.

4. In an elevator, the combination with a frame, and conveyor chains provided with load carrying flights operating vertically at each end of the frame, of a hanger guided for vertical movement at each end of the frame, means to secure said hangers at selected heights, a carrier pivotally connected from one of its ends to each of the hangers for movement from one side to the other of the frame in a substantially vertical plane, and means detachably connected to said 80 hangers for supporting the carriers in horizontal and inclined positions selectively at either side of the frame.

5. In an elevator, in combination, a conveyor-chain, load-carrying flights provided on the chain, an elevator frame guiding the chain in a substantially vertical plane, a hanger adjustably movable vertically of 90 said frame, a carrier having one end thereof pivotally connected to the upper portion of the hanger, a bar having an end thereof pivotally connected to the lower portion of the hanger, and means to connect said bar 95 intermediate its length to the free end of said carrier to support the latter in load-dislodging positions with respect to the flights, said bar also serving as a bracket to receive the loads dislodged by the carrier from the conveyor flights.

Signed at Seattle, Washington, this 15th day of October, 1925.

ERIC JOHNSON.
